(57) CLAIM

The ornamental design for a combined air fryer grill and food station, as shown and described.

DESCRIPTION

FIG. 1 is a front perspective view of a first embodiment of a combined air fryer grill and food station showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines illustrate portions of the combined air fryer grill and food station that form no part of the claimed design.

1 Claim, 5 Drawing Sheets
